(57) **CLAIM**

The ornamental design for the fifth wheel hitch plate, as shown and described.

DESCRIPTION

FIG. 1 is a top perspective view of the fifth wheel hitch plate showing our new design;

FIG. 2 is a top plan view thereof;

FIG. 3 is a front elevation view thereof;

FIG. 4 is a side elevation view thereof; the opposite side being a mirror image;

FIG. 5 is a rear elevation view thereof; and,

FIG. 6 is a bottom plan view thereof.

The dashed lines as included in the drawings do not constitute part of the claimed invention.
